PUMP IMPELLER

William H. Welsh, New York, N. Y.

Application April 20, 1945, Serial No. 589,445

4 Claims. (Cl. 103—115)

(Granted under the act of March 3, 1883, as amended April 30, 1928; 370 O. G. 757)

1

This invention relates to impellers for centrifugal pumps. In pumping corrosive fluids or slurries of abrasive material of either a corrosive or non-corrosive nature, ordinary cast-iron impellers wear to the point where replacement is necessary within a few weeks. Slurries of sand, ore and ashes, for example, are handled commonly by volute centrifugal pumps of simple design. The impellers of such pumps wear, erode and corrode at a high rate, approaching rapidly the point at which loss of efficiency results in exit velocities from the pump so low that suspended solids settle out of the slurry and clog the system. Shutdowns caused in such a manner are both long and costly, necessitating separation and cleaning of pump runners and conveyor-line-piping, in addition to replacement of the worn impeller.

The impeller life can be lengthened by casting or otherwise fabricating the entire impeller of a material more resistant to wear and corrosion than cast iron. Such a procedure, however, involves the use of a large quantity of relatively expensive material, replacement of all of which would be necessitated by only localized wear.

An object of this invention is to provide a pump impeller in which the sections most liable to wear are replaceable.

Another object is to provide a pump impeller in which the sections most liable to wear are made of material having high resistance to corrosion and abrasion, the remainder of the impeller being made of common and inexpensive material.

Still another object is to provide a pump impeller in which the sections most liable to wear are replaceable easily and quickly, without disassembling the pump housing.

Further objects and advantages of this invention, as well as its construction, arrangement and operation, will be apparent from the following description and claims in connection with the accompanying drawings, in which:

Fig. 1 is an end view of the assembled impeller of this invention, showing the inlet end;

Fig. 2 is the inlet end of the same impeller, with the seal-plate and gasket removed, partly broken away to show the relation of the replaceable parts and the vanes;

Fig. 3 is a side view of the impeller of Fig. 1;

Fig. 4 is a side view of the deflector plate of the impeller;

Fig. 5 is a side view of part of the impeller, broken away to show a vane insert recessed in the impeller body;

2

Fig. 6 is an isometric view of a wear plate of the impeller; and

Fig. 7 is an isometric view of a vane insert of the impeller.

5 In the drawings 11 represents an impeller body of ordinary design, such as is used in single-inlet, backward-discharge, volute pumps (Figs. 1 and 3). Impeller body 11 consists primarily of two parallel disk-shaped housings, that are spaced and joined by multiple vanes 12 cast integrally with the housings, said vanes forming the sides of the impeller body 11. For the purposes of illustration, the number of vanes 12 is shown as 3, although a greater or lesser number can be utilized, as desired. A single inlet opening 13 is provided in one housing of the impeller body 11, and located centrally externally of the opposite housing of impeller body 11 is hub 14, which is threaded internally to receive and engage a power shaft (not shown) by means of which rotary motion is imparted to the impeller.

Bolted or otherwise affixed to the inner surface of the housing opposite inlet opening 13 25 is a deflector plate 15. The surface of deflector plate 15 that is not adjacent to impeller body 11 is provided with a protuberant boss 16, designed to divert and direct smoothly the flow of the fluid being pumped toward the vanes and 30 periphery of the impeller (Fig. 4). Wear-plates 17, corresponding in number to vanes 12, protect portions of the inner surface of impeller body 11 opposite inlet opening 13 that are not protected by deflector plate 15. Wear-plates 17 fit 35 about the edges of deflector plate 15 and extend between the vanes 12 (Figs. 2 and 6).

40 Recesses 18 in the housing of the impeller body 11 opposite the inlet opening 13 receive the ends of vane inserts 19 (Fig. 5). Vane inserts 19, when inserted into recesses 18, form the leading edges of vanes 12. Vane inserts 19 and recesses 18 correspond in numbers to vanes 12. When in place, the outer surfaces of vane inserts 19 are flush with the outer surface of the 45 housing of impeller body 11 in which is located inlet opening 13, said housing being cut away to receive vane inserts 19. An annular gasket 20, of rubber or similar material, and an annular seal plate 21, preferably of hardened steel, are bolted to the outer surface of impeller body 11 adjacent to inlet opening 13, and serve as retaining means for the vane inserts 19. In addition, seal-plate 21 acts as a seal against the pump housing (not shown).

55 In pumping abrasive and corrosive fluids, it has

been found that almost all the wear and corrosion on the impeller takes place on the leading edges of the vanes 12, and on the inside surface of the housing of the impeller body 11 opposite the inlet opening 13, the leading edges of the vanes 12 wearing at much the greater rate. The leading edges of vanes 12 erode, corrode and wear back, reducing the efficiency of the pump to the point of uselessness in a short length of time, at the end of which period the remainder of the impeller, with the exception of the surface opposite the inlet entry, is found to be in substantially its original condition.

In utilizing this invention, impeller body 11 can be made of ordinary cast iron, or similar inexpensive material. Deflector plate 15, wear plates 17 and vane inserts 19 are made of material highly resistant to corrosion and wear, the choice of material for these parts depending on the type of fluid or slurry the impeller is intended to pump. For example, in pumping a slurry of power-plant ashes in salt water, ordinary cast-iron impellers wear to the point of uselessness within 3 weeks. It has been found that sand-cast white iron or chilled cast iron carrying 4.00 to 6.00% nickel and 1.25 and 2.25% chromium withstands the destructive action of such a slurry for periods as long as year. In utilizing the impeller of this invention for pumping such a salt-water-ash slurry, deflector plate 15, wear-plates 17, and vane inserts 19, are made of the resistant material described, or of similar material.

In assembling the impeller of this invention, deflector plate 15 and wear-plates 17 are bolted to impeller body 11. Vane inserts 19 are then inserted in place, and gasket 20 and seal-plate 21 are bolted to impeller body 11. The pump casing (not shown) is then assembled about the impeller and the power shaft is inserted through the casing into hub 14. After a period of operation, the impeller can be inspected by removing the runner or line leading to inlet opening 13 and the condition of the impeller observed through inlet opening 13.

When required, vane inserts 19 can be removed and replaced easily and quickly through the aperture in the pump casing made by removing the inlet runner or line. This is accomplished by removing seal-plate 21 and gasket 20 from the impeller body 11, withdrawing the worn vane inserts 19 and replacing them with new ones, and then replacing gasket 20 and seal-plate 21. When inspection reveals the necessity, the pump housing can be disassembled, the impeller removed, and deflector plate 15 and wear-plates 17 replaced. By securing deflector plate 15 and wear-plates 17 with stud bolts rather than with bolts and nuts, they too may be replaced through inlet opening 13, although the difficulty of so doing may in some cases outweigh the saving of labor and time resulting from not disassembling the outer case of the pump.

It will be apparent that the impeller of this invention, comprising an impeller body 11 of inexpensive material and low resistance to wear and corrosion, will operate without servicing or replacement for as long a period of time as would an impeller made entirely of the resistant material used in deflector plate 15, wear-plates 17 and vane inserts 19. When vane inserts 19 have become badly worn, a period which would mark the end of the useful life of an integral impeller, even made of resistant material, the vane inserts 19 can be removed and replaced easily

and quickly by disconnecting the inlet runner or line to the pump and removing seal-plate 21 and gasket 20. This represents a saving not only over the cost of a new impeller in its entirety but also a great saving in labor costs and shut-down time. For example, in one installation it has been found that the vane inserts 19 can be removed and replaced and the pump placed back in operation in one third the time required to disassemble the outer case of the pump and replace the impeller. Furthermore, when in addition to vane inserts 19, deflector plate 15 and wear-plates 17, or any of them, are found to become so worn as to require replacement, they can be replaced in impeller body 11, and the impeller body 11, the largest and heaviest part of the impeller, can serve for a very long period of time.

It is to be understood that various modifications and changes can be made in this invention without departing from the spirit and scope thereof as set forth in the claims.

The invention described herein may be manufactured and used by or for the Government of the United States of America for governmental purposes without the payment of any royalties thereon or therefor.

I claim:

1. A pump impeller for pumping fluids of a corrosive and abrasive nature comprising an impeller body provided with an inlet opening and multiple vanes, replaceable parts lining the inner surface of said impeller body opposite said inlet opening, replaceable inserts constituting the leading edges of said vanes, and an annular seal-plate surrounding the inlet opening of said impeller body, said seal-plate constituting the retaining means for said vane inserts and being detachable from the rest of said impeller to permit removal and replacement of said inserts, and said replaceable parts and said replaceable inserts being made of material more highly resistant to wear and erosion than is said impeller body.

2. A pump impeller for pumping fluids of a corrosive and abrasive nature comprising an impeller body provided with an inlet opening and multiple vanes, replaceable parts lining the inner surface of said impeller body opposite said inlet opening, replaceable inserts constituting the leading edges of said vanes, and an annular seal-plate surrounding the inlet opening of said impeller body, said seal-plate constituting the retaining means for said vane inserts and being detachable from the rest of said impeller to permit removal and replacement of said inserts, said impeller body consisting of cast iron, and said replaceable parts and said replaceable vane inserts consisting of sand-cast white iron containing 4.00 to 6.00% nickel and 1.25 to 2.25% chromium.

3. A pump impeller comprising an impeller body provided with an inlet opening and multiple vanes, and replaceable inserts constituting the leading edges of said vanes, said inserts being positioned at their ends in recesses in said impeller body and being held from radial motion during rotation of said impeller by the walls of said recesses.

4. A pump impeller comprising an impeller body provided with an inlet opening and multiple vanes, and replaceable inserts constituting the leading edges of said vanes, said inserts being positioned at their ends in recesses in said impeller body and being held from radial motion during

2,440,817

5

rotation of said impeller by the walls of said recesses and being removable axially of said impeller through said recesses at one end of said impeller.
